UNITED STATES PATENT OFFICE

ROBERT MONSCH, OF UNION CITY, NEW JERSEY, ASSIGNOR TO DUPLEX SAFETY WINDOW CORPORATION, OF JERSEY CITY, NEW JERSEY, A CORPORATION OF DELAWARE

WINDOW CASING

Application filed January 26, 1929. Serial No. 335,167.

This invention relates to sashes and frames for conventional types of windows, and more particularly to double hung windows in which two sashes are independently slidable between vertical frame members.

The present demands in such structures include weather proofing devices capable of excluding moisture and wind effectively, and, on the other hand provide means for adequate 10 ventilation when required.

It is also desirable that either sash may be raised and lowered easily and smoothly without binding or appreciable wear or corrosion of the parts in frictional contact.

15 It is further regarded as highly advantageous to arrange that portion of the sash containing the glazing in such manner as to pivot inwardly, thus presenting both sides of the pane for the purpose of cleansing, avoiding 20 the usual hazards and inconvenience encountered in such operations, the sash being automatically locked when in an upright position.

These and many other important and desirable features, which will become evident 25 as the description progresses, are accomplished by the novel and practical construction, arrangement and combination of parts as hereinafter described and illustrated in the 30 accompanying drawings, constituting a material portion of this disclosure, and in which:—

Figure 1 is a sectional perspective view of a 35 double hung window as made in accordance with the invention.

Figure 2 is a sectional view taken in a vertical plane indicated by the line 2—2 of Figure 1.

Figure 3 is a perspective view, drawn to a 40 smaller scale, of the metal parts of one side of the window sash.

Figure 4 is a transverse sectional view of the sashes and frame at one side of a window, showing one form of construction.

45 Figure 5 is an enlarged fragmentary side elevational view of the sash braces shown in an inclined, operative position.

Figure 6 is a transverse sectional view taken on line 6—6 of Figure 5.

50 Figure 7 is a sectional view, similar to Fig-

ure 4, but showing a modified form of construction.

Figure 8 is another like sectional view of a further modification of construction.

It is to be noted that the drawings show 55 the window frame stiles, designated by the numeral 10, as flat, level and unbroken by rabbeting or grooving at their inner surfaces to receive parting strips, therefore being stronger and less expensive to produce than 60 usual.

These stiles connect between a lintel, not shown, and sill 11 in the ordinary manner. Secured to the adjacent sides of the stiles are plain rectangular outer retaining strips 12 65 and at the front are moulded inner retaining strips 13, intermediate of which are parting strips, generally designated by the numeral 14, and which will be described in detail later on. 70

The sashes 15 and 15', respectively inner and outer, contain glass panes 16 and 16' held in the usual manner as indicated, and it will be seen that the inner sash 15 is wider than the outer sash 15', so that the outer sash, as will be shown later, may be swung between the lower stiles 38, and their protruding parts 42, thus permitting the cleaning of the upper glass also from the interior while standing on the floor. 75

Both sashes contain recesses 17 midway in the length of their side members, see Figure 2, and at their upper corners are angular recesses 18; other transverse recesses 19 are formed in their bottoms to extend in from each side. 80

85 Fixed to the outer edges of the sashes are metal plates 20—20' having in reaching right angular elements 21 provided with upstanding members 22 extending into the recesses 19.

90 The central portions of the plates 20 are offset inwardly, as at 23, to extend into the recesses 17, the offset portions 23 containing longitudinal slots 24 in the inner edge of which are a series of notches 89 their purpose 95 becoming later apparent.

A metal chain holder strip 26 is fixed on the upper portion on the outer side of the plate 38, the lower end of the strip terminating in a prong 27 to engage a loop 28 at the end of 100

a sash cord or chain 29, arranged in the usual manner.

A spring strip 30 is fixed at its lower end on the inner side of the plate 20, the upper end of the strip being bent inwardly to cover the opening leading to the recess 18 and is provided with a finger grip 31 by which the spring strip may be sprung into the recess and carry with it a latch pin 32 fixed in the outer side of the strip to pass freely through registering openings 88 in the plates 20 and 38 and strip 26.

The parting strip 14, as seen in Figures 1 and 4, is formed of sheet metal to produce a rectangular inreaching member having a straight flat outer face 33, right angular sides 34—34' creased inwardly at both sides to constitute channels 35—35', and then flanged outwardly at 36—36', these flanges being firmly held against the frame stile 10 by screws 37 passing centrally through the face 33.

An integral inner sash guide member is formed of sheet metal to present a face 38 arranged closely adjacent the plate 20, one edge of the guide being bent at a right angle 39 to contact the side of the inner retaining strip 13 and provided with a flange 40 to contact the stile 10, the guide face 38 being in the plane of the strips 13 and 14.

The opposite side edge of the guide 38 is extended outwardly to form a loop 41 loosely engaging over the extending edge of the plate 30, presenting a weather obstructing joint, 35 then folded tightly re-entrantly upon itself as at 42, the outer surface of the doubled loop being in register with the outer surface of the parting strip 14, a continuation of the loop making contact with the face 33 of the strip, thence to be turned at a right angle at 43 to engage the front side 34 of the strip and terminate in an outturned flange 44 engaged in the front channel 35 of the parting strip as best seen in Figure 4, providing an 45 effective weather proof joint.

The outer sash guide presents a face 45, its front edge being bent to form an angular member 46 making contact with the rear side 34' of the parting strip 14 and having an outturned flange 47 to interengage in the rear channel 35' of the parting strip.

The opposite, outer edge of the guide is continued outwardly to form a loop 48 loosely engaging over the extending edge of the plate 20', the material being turned closely re-entrantly upon itself, as at 49, so that the outer surface of the doubled loop contacts with the face of the outer retaining strip 12, thereafter being bent, at a right angle, as at 50, to contact the forward surface of the strip and terminating in a flange 51 contacting the stile 10.

From the foregoing it will be seen that the guides are interengaged by the parting strip

14 by metal surfaces and held against the stile with sufficient tension to move smoothly, the shape of the flattened loops preventing the entrance of wind and rain.

Furthermore that the guide rails for the sash slides, which are only one for either sash, namely 34 and 34' respectively, run in rather shallow grooves, entirely hidden from atmospheric influences and dust, and for these combined reasons will neither jam nor corrode or stick.

The doubling up of the sheet metal on the channels in which the sash plates 20 and 21 repose, makes these parts of the stiles extra-strong, guarding against collapse and resultant jamming, while the peculiar shape effectively excludes any access of moisture or dust to the inclosed contacting strip.

In the modification shown in Figure 7 the same general structure is employed, but the parting strip 14 is shaped to avoid the channels 35—35', the side walls 55 of the strip extending straight to the stile 10 where they are outturned and bent re-entrantly, as at 56, to enclose the corresponding flanged edges 90 of the sash guide elements, this form being less difficult to construct and equally effective in the results attained.

The further modification disclosed in Figure 8, shows a parting strip formed to present projecting double angular guide elements 65 extending the full length on both sides of the strip and the contacting elements of the sash guides 66—67 are correspondingly formed to engage thereover, thus constituting a practical embodiment of the device.

Fixed on the side of the elements 38 of the sash guides, near their lower ends, are strip brackets 80 in which are secured bars 81 passing freely through openings in the guides and plates 20, into the recesses 19, the inner ends of the bars being journaled in the members 22, thus providing means for folding the sashes inwardly at will.

In order to support the sashes when in an inclined position an arm 82 is pivoted on the sash guides 38, as at 83, the reduced, free end 84 of the arm extending outward for convenience in operation.

Fixed in the arm, near its outer end, is a stud 85 passing freely in the slot 24 of the sash plate element 23 and adjustably receivable in any of the notches 25 of the slot.

Carried at the outer end of the stud 85 is a fixed washer 86, maintaining the arm in close but movable relation to the plate, and fixed in a slot in the washer 86 is a bent flat spring 87, its ends pressing against the edge of the slot, opposite the notches to urge the stud into engagement therewith, thus constituting an effective device for holding the sash at any desired inclination, providing for ventilation and permitting the sashes to be turned inwardly at an angle up to 90 degrees.

A little consideration will show that, when

the sash is tilted inwardly, the stud will automatically engage the first uppermost notch only, and to release it, either to close the window or to bring the stud further down into a deeper notch, the extension 84 of the lever arm must be pressed down momentarily to disengage the stud and hold the spring compressed while tilting the sash.

At the upper portion of the guides 38 and 45 are slots 88 receptive of the latch pin 32 when the sash is in an upright position, positively locking it against movement relative to the sash, the pin being slightly tapered off at the end, as indicated, so as to automatically snap into engagement with the slot and to be retracted by pressing the spring 30-31 inwardly.

The device is so designed and constructed as to permit the outer sash to swing inwardly whether it is kept above or lowered while the inner sash is raised above it, thus enabling ready washing of the window conveniently and safely; ventilation may be secured without draught by slightly inclining either sash. The construction is adapted to wear indefinitely and prevent rattling, as well as any entrance of storm water or wind.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described the invention, what is claimed as new and desired to secure by Letters Patent, is:—

1. A window comprising a frame having flat surfaced stiles, inner and outer sash retaining strips, an intermediate all-metal parting stud having channelled sides, shaped so as to form weather-proof sash runways inner and outer sashes, metallic guides for each sash, provided with inwardly opening channels, forming weather-guards for said sash and means formed on said guides to slidably engage the channelled sides of said parting stud.

2. A window comprising a frame having flat surfaced stiles, inner and outer sash retaining strips, an intermediate all-metal parting strip having channelled flanges at its base, forming weather-proof sash runways, an inner sash, an outer sash of lesser width than the inner sash, said sashes being pivoted between said guides, means to normally hold the sashes upright, metallic guides for each of said sashes, provided with inwardly opening channels, forming weather-guards for them and co-operative means on said guides and parting stud for interengagement.

3. A window frame having a central metallic parting studs provided with channelled flanges at its base, sashes on opposite sides of

said stud, said sashes being pivotally movable on a horizontal axis, the inner sash being of greater width than the outer sash, plates fixed on the side edges of each sash, said plates having their rear edges extended outwardly beyond the sash, sheet metal sash guides having doubled channelled elements opening inwardly to engage the extending edges of said plates, extensions on said guides to contact the outer sash stops, and other extensions shaped to conform and engage the sides of said parting stud.

4. A window frame having a central metallic parting studs provided with channelled flanges at its base, sashes on opposite sides of said stud, said sashes being pivotally movable on a horizontal axis, the inner sash being of greater width than the outer sash, plates fixed on the side edges of each sash, said plates having their rear edges extended outwardly beyond the sash, sheet metal sash guides having doubled channelled elements opening inwardly to engage the extending edges of said plates, said guides and doubled channelled elements being so arranged that the inner channelled element does not protrude inwardly beyond the side edge plate of the outer sash, and operative means to tilt the sashes inwardly over their horizontal axis.

5. A window frame having a central metallic parting stud, provided with channelled flanges at its base forming weather-proof sash runways, hollow metallic sash guides, adapted to serve as sash weight boxes, and provided with inwardly opening channelled weather-guards, cooperative means between said sash guides and said runways, sashes on opposite sides of said parting stud, metal plates fixed on the side edges of said sashes and operatively engaging the weather-guards of the sash guides, pivotal means at the lower ends of said plates to connect said sashes to the sash guides, spring latches, adapted to automatically lock the upper ends of said plates to the guides when sashes are brought into an upright position, and cord-engaging means on said guides.

6. A window frame having a central metallic parting stud, provided with channelled flanges at its base, forming weather-proof sash runways, hollow metallic sash guides, adapted to serve as sash weight boxes, and provided with inwardly opening channelled weather-guards, cooperative means between said sash guides and said runways, sashes on opposite sides of said parting stud, metal plates fixed on the side edges of said sashes and operatively engaging the weather-guards of the sash guides, pivotal means at the lower ends of said plates to connect said sashes to the sash guides, arms pivoted to said guides, studs pivotally fixed in said arms, the arms being extended beyond the pivotal point of said studs and forming manipulating han-

dles, the sash plates having longitudinal slots through which the studs pass, said slots being provided with lateral notches, means carried by said studs to urge them into engagement with the notches, and cord-engaging means on the sash guides.

7. A window frame having inner and outer sash-retaining strips, a central sheet-metal parting stud, hollow sheet-metal sash guides, weather-proof runways, formed and inclosed between the parting stud and the sash guides, sashes pivoted between said guides, straight sheet-metal contact plates, fixed on the side edges of the sashes and extending outwardly beyond the sash frames, channels formed on the contact faces of the sash guides by doubling up the sheet-metal and enveloping the outward-extensions of said contact plates, means to automatically retain said sashes at any inclination, and means to automatically fasten them in the sash frame, when they are brought into a vertical position.

In testimony whereof I affix my signature.

ROBERT MONSCH.
